UNITED STATES PATENT OFFICE.

BENJAMIN O. FOX, OF MILWAUKEE, WISCONSIN.

TELEPHONE.

SPECIFICATION forming part of Letters Patent No. 733,021, dated July 7, 1903.

Application filed July 11, 1902. Serial No. 115,137. (No model.)

To all whom it may concern:

Be it known that I, BENJAMIN O. FOX, a citizen of the United States, and a resident of Milwaukee, in the county of Milwaukee and State of Wisconsin, have invented certain new and useful Improvements in Telephones; and I do hereby declare that the following is a full, clear, and exact description thereof.

My invention relates to improvements in telephones, and has for its object to provide a simple and effective means of signaling the central office by means of mechanism attached to the receiver, and is especially adapted for use in hotels, factories, and public buildings where a special telephone system is required.

In the drawings, Figure 1 is a top view of a receiver with the cap removed, showing my device. Fig. 2 is a sectional view on line 22 of Fig. 1, and Fig. 3 is a diagram view.

As shown, A is a receiver, and B is an operating-spring, with its lower end secured to the receiver on the inside and its free end resting on a contact-point c, and thus through wire 1 and wire 2 establishes an alarm-circuit for the subscribed station.

Secured to the outer surface of spring B is a strip of non-conducting material a, which extends through a cut-out portion in the receiver and beyond the outer surface thereof, furnishing means whereby the said spring is actuated. Secured to the inner surface of spring B at a point near its free end is a plate b, which is insulated from the said spring, the object of which is hereinafter explained.

Secured to the inner surface of the receiver at right angles to the free end of said spring B from the center of said receiver is a spring C, which has a conducting-wire secured thereto and in circuit with the alarm mechanism at the central office.

When spring C is normal, it has an open circuit; but it is so constructed that its free end extends across the path of the free end of spring B in a manner so that when the latter has been pressed inward—say half-way—the point of spring C will contact with the surface of spring B at a point near the outer edge and directly opposite the plate b, and thus through their connections, wire 3 and wire 1, establishes a circuit with the alarm mechanism at the cen-

tral office. When spring B has been pressed inward its prescribed distance, the plate b will have come into contact with spring C at a point nearer to its secured end than is the point of its contact with spring B, and thereby forced the point of the former free from the latter, and thus breaks the signal-circuit. At the same time the free end of spring B has come into contact with spring D, which said spring also lies across the path of travel of the former and is secured to the inner surface of the receiver at a point directly opposite from the fastening of spring C. In this manner through wires 1 and 4 a talking-circuit is established through the central office.

The operation of my device is as follows: Press the plate a, which will force the spring B free from the contact-point c, and as the former continues on its forward travel will first contact with spring C, thus making the circuit with the alarm system at central station and send in its alarm, and as spring B continues on its travel plate b comes in contact with spring C and forces the latter free from spring B, thus breaking the latter circuit. Second spring B will contact with spring D, thus forming a talking-circuit through central station, spring B all the time holding spring C suspended against plate b. Should the alarm not be heard at central station, another alarm may be sent in by repeating the operation.

Having thus described my invention, what I claim, and desire to secure by Letters Patent, is—

1. The combination with a receiver of a spring, laterally secured to the inside thereof, a contact-point for engagement with said spring; an insulated plate secured to the inside of said spring; another spring adapted to engage the said spring and the said plate at different points; another spring for engagement with the first-mentioned spring and means for manually operating the latter substantially as set forth.

2. The combination with a receiver, of a spring laterally secured to the inside thereof, a contact-point for engagement therewith, an insulated plate secured to the inside of said spring; another spring extending across the

path of travel of the latter and adapted to engage the said spring and the said plate at different points of travel, another spring extending across the path of travel of the first-
5 mentioned spring and means for operating the latter from the exterior of the receiver substantially as set forth.

In witness whereof I affix my signature in presence of two witnesses.

BENJAMIN O. FOX.
